UNITED STATES PATENT OFFICE

ARTHUR LIEBERHERR, OF WINTERTHUR, SWITZERLAND, ASSIGNOR TO THE FIRM OF SULZER FRERES SOCIETE ANONYME, OF WINTERTHUR, SWITZERLAND

HIGH PRESSURE WATER TUBE STEAM GENERATOR

Application filed December 2, 1930, Serial No. 499,454, and in Switzerland December 6, 1929.

This invention relates to high pressure water tube steam generators, and has for its object to overcome the pulsations to which such generators are at present liable and which are caused when the tube becomes filled with steam which suddenly escapes so that the consequent rapid inflow of water reduces the effective super-heating area. Such pulsations are further increased by the geyser action caused by a considerable length of tube being suddenly filled with steam which prevents the flow of feed water, this action, as is well known, being stronger the lower the working pressure and the greater the length of the tube to be heated.

According to this invention fluctuations in the evaporation of the steam due to unstable equilibrium of flow are prevented by introducing the main portion of the working medium at the inlet end of a high pressure water tube steam generator whence it flows without being throttled to the outlet end of the tube and is there discharged in the form of dry steam, an additional minor quantity of working medium being constantly introduced into the system of tubes at at least one point between the inlet and outlet ends, preferably through inlets of narrow cross-section. Preferably some of the additional working medium is introduced into the generator at or near the point at which the working medium is converted from a liquid into a vapour, the pipes for supplying this additional medium being preferably provided with a throttling device or constricted passage so that the amount of medium introduced at each individual point can be regulated at will.

This arrangement enables the pulsations which would otherwise occur in the steam generator to be damped to a considerable extent, as the regulation which automatically takes place at each fall of pressure is effected in a steady and regular manner which will not interfere with the super-heating.

A construction according to this invention is diagrammatically illustrated by way of example in the accompanying drawing, 50 in which

Figure 1 is a vertical section, Figure 2 shows on an enlarged scale a throttling point in section,

Figure 3 shows diagrammatically a modification of the arrangement illustrated in Figure 1,

Figures 4 and 5 are sections through a pipe coil showing the zone within which water is converted into steam, and

Figure 6 shows the same zone of a steam generator constructed in accordance with the detail shown in Figure 2.

The high pressure steam generator illustrated comprises a coiled pipe 1 enclosed in a casing, for example, of masonry 2 or other heat-insulating material. Any suitable source of heat may be used, such for example a liquid, gaseous or pulverized fuel, in the example diagrammatically shown a burner 3 being employed supplied through a pipe 4. The air to support combustion is admitted into the burner through a pipe 5 so that it is mixed with the fuel and passes in the form of a combustible mixture into the combustion chamber 6 of the steam generator.

The burnt gases are either discharged direct through the chimney 7 or passed through a feed water heater or other device by which their waste heat is utilized.

A feed water pump 8, shown as a centrifugal pump supplied with liquid through the pipe 9, delivers feed water through the pipe 10 into the steam generating coil 1, the liquid delivered being regulated by a device 11 interposed between the pump and the supply pipe 10. The steam generated is delivered to the points of consumption through the pipe 12.

For introducing additional feed water a pipe 14 is provided which is in communication with the steam generator coil 1 and provided with a throttling device 15 by which the quantity of liquid introduced through the pipe 14 can be regulated. The adjustment of the cross-sectional area of the pipe may be effected in any way, as for example by means of a perforated disc 16 shown in Figure 2.

Figure 3 shows an alternative arrange-

ment in which in addition to the feed water introduced through the normal inlet 17 small quantities of feed water are introduced into the pipe coil 1 through additional 5 supply pipes 14 each provided with a throttling device as shown.

Figure 4 shows in development part of a pipe coil in which the working medium is in a liquid state up to the point *a* after which 10 it passes into a state of evaporation. Pulsations may cause the feed water to shoot forward or advance up to a new limit *b* (Figure 5) which would alter the boundary between the state of liquid and vapour, thus 15 reducing the effective length of the pipe coil capable of being used for superheating.

According to the present invention these pulsations are prevented or damped by supplying the feed medium in small quantities, 20 one such quantity being introduced at the point *c* in addition to the main feed water introduced at 17.

As will be seen from Figure 6, which represents a development of that part of the 25 steam generator enclosed within the circle in Figure 1, the working of the steam generator takes place in the following manner.

When, owing to a rapid discharge of steam, pressure is reduced, an abnormal 30 quantity of feed water will flow through the pipe 20 and will retard the generation of steam to a corresponding extent. In this way the pipe friction will be again increased owing to the presence of more water in the 35 pipe and the supply through the branch pipe will be reduced so that the generation of steam will again increase but inrush of water such as is indicated at Figure 5 will be prevented or at least reduced.

40 The introduction of small quantities of feed water, which in certain circumstances may be very small quantities, takes place at or about the boundary between the steam and water zones. Owing to the pulsations 45 being avoided or reduced, loss of superheating area is obviated and consequently the boundary between the water and steam zones and hence the point at which steam generation and superheating begin are maintained substantially constant.

50 It will be understood that the source of heat may be other than that illustrated and if desired could be disposed in the upper part of the generator casing whether the feed water is supplied from the top or from the bottom. Any desired number of pipe coils can be used connected together in parallel or in series in accordance with the output required and feed water heaters may be 55 arranged in any well known manner without departing from the invention.

I claim:

1. In a high pressure water tube steam generator, in combination means for introducing feed water at the inlet end of the tube

system through which it flows without being throttled to the outlet where it is discharged as steam and means for constantly and continuously introducing an additional quantity of feed medium into said tube system through narrow invariable transverse sections at at least one point between the inlet and outlet end of said tube, additional medium being introduced in the form of a jet compounded with the main body of working medium, whereby the supply of additional water is controlled in accordance with the varying density and state of matter of the main body of working medium. 70

2. In a high pressure water tube steam generator, in combination means for introducing feed water at the inlet end of the tube system through which it flows without being throttled to the outlet where it is discharged as steam and a pipe of reduced 75 fixed cross-section for continuously introducing an additional quantity of feed medium into said tube system at a point between the inlet and outlet end of said tube, additional medium being introduced in the form of a jet compounded with the main body of working medium, whereby the supply of additional water is controlled in accordance with the varying density and state of matter 80 of the main body of working medium. 85

3. In a high pressure water tube steam generator, in combination means for introducing feed water at the inlet end of the tube system through which it flows without being throttled to the outlet where it is discharged as steam and pipes of reduced 90 fixed cross-section for continuously introducing an additional quantity of feed medium into said tube system at points between the inlet and outlet end of said tube, additional medium being introduced in the form of a jet compounded with the main body of working medium, whereby the supply of additional water is controlled in accordance with the varying density and state of matter 95 of the main body of working medium. 100

4. In a high pressure water tube steam generator, in combination means for introducing feed water at the inlet end of the tube system through which it flows without being throttled to the outlet where it is discharged as steam and means for continuously introducing an additional quantity of feed medium into said tube system through a constricted, fixed-size passage near a point where 105 the working medium is converted from a liquid into a vaporous state, additional medium being introduced in the form of a jet compounded with the main body of working medium, whereby the supply of additional water is controlled in accordance with the varying density and state of matter of the main body of working medium. 110

5. The improvement in the method of regulating high pressure water tube steam gen- 115

erators of the kind in which the main quantity of feed medium is introduced at the inlet end of the tubes through which it flows without being throttled to the outlet end,
5 where it is discharged as steam, by means of an additional quantity of feed medium introduced into the tube system between the inlet and outlet ends of the tubes, comprising introducing constantly the additional
10 quantity of feed medium through passages of narrow and unalterable cross section in order to regulate the quantity of additional feed medium by means of the changes in the resistance to flow arising when the condition
15 of the main quantity of working medium alters as it flows past the spot where the additional feed is introduced.

In testimony whereof I have affixed my
signature.
